PENCIL CLEANER

George L. Gage, 890 Victoria Ave., Los Angeles, Calif.
Filed June 11, 1962, Ser. No. 291,391
8 Claims. (Cl. 15—210)

This invention relates generally to pencil cleaning devices and relates more particularly to devices for easily cleaning the ends of pencils that have just been sharpened.

While the invention has particular utility in connection with the cleaning of newly sharpened points of lead pencils and is shown and described in such connection, it is to be understood that its utility is not confined thereto.

As is well known, there is the problem with newly sharpened lead pencils, the sharpening resulting in a certain amount of finely powdered lead getting on the adjacent portion of the pencil. Should the pencil then be used a certain amount of this powdered lead will get on the user's fingers and in many cases will get onto the paper being worked with, so that that paper becomes smudged. Draftsmen find this problem particularly bad when working with large drawings and it is necessary to sharpen the pencils used a great many times before the drawing is completed.

It is therefore an object of the present invention to provide a device that may be kept close at hand whereby the finely powdered dust on the sharpened end of a newly sharpened pencil may be easily and quickly removed.

It is another object of the invention to provide a device of this character having a chemical free cleaning element operably held in a holder therefor.

It is still another object of the invention to provide a device of this character having a cleaning element that may be easily and quickly inserted into the holder and easily and quickly removed therefrom for washing or otherwise cleaning same or for replacement purposes.

It is a further object of the invention to provide a device of this character having means for releasably retaining the cleaning element in the holder.

It is a still further object of the invention to provide a device of this character wherein the holder is hollow and the axis thereof is upwardly and forwardly inclined at a convenient angle for use with the large end faces upwardly.

It is a still further object of the invention to provide a device of this character wherein the lower smaller end of the holder is open and the cleaning element is so arranged in the holder that a pencil point may be pushed through the cleaning element into the smaller opening and retracted, thereby wiping said point clean without rotating the pencil.

Another object of the invention is to provide a device of this character having a base for supporting a pencil sharpener in close proximity to the holder in which the cleaning element is disposed.

Still another object of the invention is to provide a device of this character that is extremely simple in construction.

A further object of the invention is to provide a device of this character that is relatively inexpensive to manufacture.

The characteristics and advantages of the invention are further sufficiently referred to in connection with the following detailed description of the accompanying drawings, which represent one embodiment. After considering this example, skilled persons will understand that variations may be made without departing from the principles disclosed, and I contemplate the employment of any structures, arrangements or modes of operation that are properly within the scope of the appended claims.

2

Referring to the drawings, which are for illustrative purposes only:

FIG. 1 is a perspective view of a device embodying the present invention;

5 FIG. 2 is an enlarged front elevational view with a portion broken away and shown in section;

FIG. 3 is an enlarged sectional view taken on line 3—3 of FIG. 1;

10 FIG. 4 is a top plan view of the cleaning element laid out flat; and

FIG. 5 is an alternative arrangement.

Referring more particularly to FIGS. 1, 2 and 3, the device is shown as having a rectangular base with rounded corners, there being a depending peripheral supporting flange 11. Flange 11 is inclined downwardly and outwardly and the lower edge thereof is adapted to rest on the top of a table or other support.

Adjacent one end of the base is an upstanding boss or lug 12 having rounded upper corners 14 and being arcuately curved at 15 intermediate said corners and providing an arcuate top surface intermediate the side edges of the boss which is generally inclined towards a front side of the base and upwardly away from the adjacent upper surface of the base. The base with its flange and the boss or lug 12 may be of any suitable material, such as a relatively stiff or rigid plastic. It is to be understood, of course, that other materials may be used.

Boss 12 supports a holder 16 for a cleaning element, indicated generally at 17.

Holder 16 is hollow and is frusto-conical in shape with the large and small ends open, said holder being cradled at a point spaced from its larger open end on the curved portion 15 of the boss 12 and secured thereto by any suitable means. As shown, the holder is of plastic and may be attached to the boss 12 by means of any suitable adhesive, there being various well known adhesives which will effectively bind or secure the parts together.

The axis of holder 16 is inclined upwardly towards the front of the base so that the upper large open end 18 of the holder is upwardly facing at a convenient angle of use and the smaller open end 19 is at the bottom.

There are a plurality of flanges 21 at the upper end of the holder, said flanges extending inwardly a limited distance of the inner surface of the frusto-conical wall of the device and provide lips for releasably retaining the cleaning element 17 within said holder. Flanges 21 may be integral with the holder or they may be separate elements or parts secured to the holder by an adhesive or other suitable means.

As best shown in FIG. 4, the cleaning element is semi-circular in shape when laid out flat and has a semicircular notch 24 in the diametrical edge 25 intermediate the ends thereof. There is a backing 27 of any suitable character and attached to a pile of fibers or filaments or the like 28 at one side of the backing.

In order to insert the cleaning element into the holder 16 said element is formed into a frusto-conical shape with the diametrical edge portion at opposite sides of the notch in contact with each other, or substantially in such contact. The cleaning element, when thus formed, is inserted into the holder and it will be noted that the length of said element when formed into the frusto-conical shape is substantially the same as the length of the holder from the under sides of the flanges or lips 21 to the bottom or smaller end thereof. When thus installed in the holder the fibers or pile of fibers of the cleaning element will overlap at the bottom, as clearly shown in FIG. 3. Flanges or lips 21 will overlie upper edge portions of the backing 27 of the cleaning element when formed in the frusto-conical shape and disposed in the holder, so that said cleaning element will be effectively retained in the holder but will be readily removable there-

from by pulling the overlaid edge portions of the cleaning element from beneath said flanges or lips 21.

When the cleaning element is disposed in the holder, as shown in FIG. 3, the long fibers of the pile 28 provide a relatively soft effective overlapping wiper so that the sharpened ends of lead pencils may be pushed through the overlapping fibers so that there is no need to twist or turn the pencil to easily and quickly remove the powdered lead deposited on said sharpened ends during the sharpening operation. It will also be noted that the sharpened end may be effectively cleaned on the fibers inside the cone at any point. The pencils thus inserted into the device may, of course, be readily withdrawn and will be clean when pulled from the device.

It is to be understood, of course, that the cleaning element may be otherwise constructed, the important thing being to have a surface on which a pencil point may be easily wiped to effectively remove the lead particles thereon after a sharpening operation.

Adjacent the ends opposite the boss 12 the base is 20 provided with a circular recess 30 into which the base 32 of a pencil sharpener 33 may be placed. Thus the pencil sharpener 33 will be supported by the base 10 in close proximity to the cleaning device.

In the arrangement shown in FIG. 5, there is an annular flange 35 at the upper, larger end of the holder, said flange extending inwardly of the upper edge of said holder and functions to retain the cleaning or wiping element in said holder. This flange is shown as being integral with the frusto-conical wall of said holder although it may be a separate element secured to the holder by an adhesive or other suitable means.

The invention and its attendant advantages will be understood from the foregoing description and it will be apparent that various changes may be made in the form, 35 construction and arrangement of the parts of the invention without departing from the spirit and scope thereof or sacrificing its material advantages, the arrangement hereinbefore described being merely by way of example.

I claim:

1. A device of the class described, comprising:

- (A) a base of generally rectangular shape;
- (B) an upstanding boss on said base having an arcuate top surface intermediate the side edges thereof, said surface being inclined generally towards one side 45 of the base and away from its adjacent surface;
- (C) a hollow receptacle of frusto-conical shape open at the ends, the receptacle being secured to the arcuate surface of said boss, the axis of said receptacle being inclined upwardly towards said one side and 50 with the large open end facing upwardly at a convenient angle for the user, the curvature of the arcuate top surface of said boss conforming to the exterior shape of that portion of the receptacle received on said arcuate surface;
- (D) a plurality of annularly spaced lips extending a limited distance inwardly of the upper open end of the receptacle;
- (E) and a cleaning element of semicircular shape when flat before inserting in the receptacle, said 60 cleaning element having a semicircular notch in the diametrical side, the diametrical edge portions at opposite sides of said notch being of equal length, said cleaning element having

(a) a backing and

(b) a relatively deep pile of fibers attached at one side of said backing;

- (F) said cleaning element being formed into a frusto-conical shape open at the ends and with the diametrical edge portions at each side of the notch abutting 70 each other and said cleaning element being disposed in the receptacle with the backing engaging the inner surface of said receptacle and the fibers on the inner side of said cleaning element with the fibers at the smaller end overlapping across the opening defined

75

by the backing at said smaller end, the inwardly extending lips of said receptacle overlying edge portions of the large end of the backing to releasably retain said cleaning element in said receptacle.

2. A device of the class described, comprising:

- (A) a base of generally rectangular shape;
- (B) an upstanding boss on said base having an arcuate top surface intermediate the side edges thereof, said surface being inclined generally towards one side of the base and away from its adjacent surface;
- (C) a hollow receptacle of frusto-conical shape open at the ends, the receptacle being secured to the arcuate surface of said boss, the axis of said receptacle being inclined upwardly towards said one side and with the large open end facing upwardly at a convenient angle for the user;
- (D) a plurality of annularly spaced lips extending inwardly of the upper open end of the receptacle a limited distance;
- (E) and a cleaning element of semicircular shape when flat before inserting in said receptacle, said cleaning element having a notch in the diametrical side, the diametrical edge portions at opposite sides of said notch being of equal length, said cleaning element having

(a) a backing

- (b) and a relatively deep pile of fibers at one side;
- (F) said cleaning element being formed into a frusto-conical shape with the diametrical edge portions at each side of the notch abutting each other and said cleaning element being disposed in the receptacle with the backing engaging the inner surface of said receptacle with the pile overlapping in the small end thereof, the inwardly extending lips of said receptacle releasably retaining said cleaning element in said receptacle.

3. In a pencil cleaning device:

- (A) a base having a front side;
- (B) an upstanding boss on said base;
- (C) a receptacle of frusto-conical shape open at the ends, the receptacle being secured to said boss, the axis of said receptacle being inclined upwardly away from said base in the direction of said front side and with the large open end of the receptacle at the top;
- (D) lip means extending inwardly a limited distance of the upper open end of said receptacle;
- (E) and a flexible cleaning element disposed in said receptacle and having

(a) a relatively flat backing and

(b) wiping material on the inner side, said lip means releasably retaining said cleaning element in said receptacle.

4. In a pencil cleaning device:

- (A) a hollow receptacle with a frusto-conical interior, said receptacle being open at both ends;
- (B) a hollow cleaning element disposed in said receptacle and conforming to the interior shape of the receptacle, said cleaning element having a pile on the interior surface exposed to use from the open larger end, the pile fibers in the smaller end overlapping;
- (C) means releasably retaining said cleaning element in said receptacle;
- (D) and support means for said receptacle.

5. In a pencil cleaning device:

- (A) a hollow receptacle having an open upper end, said receptacle being upwardly inclined;
- (B) a hollow cleaning element insertable into and removable from said receptacle through said open upper end, and when inserted having wiping material exposed to said open upper end;
- (C) and means adjacent the open upper end for releasably retaining said cleaning element in said receptacle.

6. A cleaning element for cleaning pencils and the like, comprising:

- a backing;
- and a relatively deep pile of fibers on one side of said backing;
- said cleaning element being of semicircular shape when flat and having a semicircular notch in the diametrical side, the diametrical edge portions at the opposite sides of said notch being of equal length, said cleaning element being adapted to be 10 formed into a frusto-conical shape having a large end opening at one end and a relatively smaller end opening at its other end with the diametrical edge portions abutting each other and the fibers adjacent the smaller end extending into the small end opening 15 in overlapping relation.

7. An article of manufacture, comprising:

(A) a flexible generally sheet-like cleaning element having projecting flexible surface media on one side upon which the point of a pencil may be wiped, said 20 cleaning element having longitudinal edges and being shaped for forming into a generally cone-shape with opposite open ends of different size for reception in a holder with the longitudinal edges abutting and the surface media extending into the smaller 25 of said open ends.

8. In a pencil cleaning device:

(A) a hollow receptacle having an open upper end defined by an upper end edge;

5

(B) a hollow cleaning element disposed in said receptacle and having projecting flexible wiping material on the inner side exposed to said open upper end;

(C) an integral annular flange at the upper end of said receptacle extending a limited distance inwardly from the upper edge of the open upper end for releasably retaining the cleaning element in said receptacle;

(D) and means for supporting said receptacle at a point spaced from said upper edge.
